UNITED STATES PATENT OFFICE.

ELZY R. WILLIAMS, OF ST. JOSEPH, MISSOURI.

TRIGGER MECHANISM.

1,243,120.

Specification of Letters Patent. Patented Oct. 16, 1917.

Application filed June 18, 1917. Serial No. 175,331.

To all whom it may concern:

Be it known that I, ELZY R. WILLIAMS, a citizen of the United States, residing at St. Joseph, in the county of Buchanan and State of Missouri, have invented a certain new and useful Improvement in Trigger Mechanisms, of which the following is a specification.

My invention relates to improvements in trigger mechanisms.

One of the objects of my invention is to provide a trigger mechanism, of the type having a main trigger and an auxiliary or hair trigger, which is reliable in operation, which is easily operated, which is not liable to get out of order, and which may be readily applied to fire-arms now in use.

The novel features of my invention are hereinafter fully described and claimed.

In the accompanying drawings, which illustrate the preferred embodiment of my invention, as applied to a fire-arm having a sliding hammer,

Figure 1 is a side elevation of a portion of a fire-arm which is provided with my improvement.

Fig. 2 is a rear view, partly broken away, of my improved trigger mechanism.

Fig. 3 is a front view, partly broken away, of the trigger mechanism.

Fig. 4 is an inside elevation of the cover of the main trigger.

Fig. 5 is a cross section on the line 5—5 of Fig. 7.

Fig. 6 is a side elevation of the main trigger and parts connected therewith, portions being broken away, and some of the parts removed.

Fig. 7 is an enlarged view, partly in side elevation and partly in vertical section, of a portion of a fire-arm provided with my improvement. In this view, the parts controlled by the auxiliary trigger are shown in the released position.

Fig. 8 is a view similar to Fig. 7, the auxiliary trigger and mechanism controlled thereby being shown in the set position.

Similar reference characters designate similar parts in the different views.

1 designates the sliding hammer of a fire-arm of the Springfield 1903 type. 2 designates the sear pivoted on the usual pin 3 and normally forced by a coil spring 4 into position for engaging the hammer 1, when the latter is cocked, as in Fig. 7.

The main trigger comprises a plate 5,

which adjacent to its upper end is pivoted to the sear 2 by a transverse pin 6, and a removable cover 7, best shown in Fig. 4, which is releasably secured to the plate 5 by 60 screws 8, Fig. 1.

The upper end of the plate 5 is provided with a slot in which is mounted an auxiliary releasing member, preferably comprising a releasing lever 9, which is pivoted to the 65 plate 5 by a transverse pin 10. The releasing lever 9 carries a transverse pin 11 on which is mounted a friction roller 12, which is adapted to strike against an abutment comprising a fixed part 13 of the fire-arm, 70 when the releasing lever 9 is swung to the releasing position, shown in Fig. 6.

When the releasing lever 9 is swung to the position shown in Fig. 6, it will force downwardly the main trigger, which in turn will 75 swing the sear 2 to the released position against the tension of the spring 4.

The upper end of the main trigger plate 5 also has a bearing against the fixed abutment 13, so that when the main trigger is 80 pulled, it will force the sear 2 out of engagement with the hammer 1.

For swinging the releasing lever 9 to the releasing position shown in Fig. 6, the following described spring actuated mechanism 85 is provided.

Mounted in the chamber formed by the plate 5 and cover 7 of the main trigger, is an operating member comprising preferably an operating lever 14, which is pivotally 90 mounted upon a screw 15, which is secured to the plate 5.

Secured to the plate 5 by a screw 16 is a spring 17 having an arm 18 which bears against a pin 19 which is secured to the plate 95 5. The spring 17 is provided at its free end with a slot 20, Fig. 2, in which is mounted a link 21 which is pivoted by a pin 22 to the operating lever 14, and which has mounted in it a pin 23, against which bears the rear 100 side of the spring 17.

The link 21 is located below the pivot screw 15, so that when the lower end of the operating lever 14 is swung forwardly to the position shown in Fig. 8, the spring 17 will 105 be placed under tension through the intermediary of the link 21.

For holding the operating lever 14 in the set position, shown in Fig. 8, there is pivoted to the lever 14 by means of a transverse pin 24, an auxiliary or hair trigger 25 which is provided with an arm 26 which in

the set position engages a plate 27 fixed to the plate 5 and which constitutes a fixed abutment.

A spring 28 secured to the operating lever 14 bears against the auxiliary trigger 25 at a point above the pin 24, so as to force the upper end of the auxiliary trigger rearwardly against a stop pin 29, and so as to force the auxiliary trigger into a position in which it will engage the abutment 27, when the lever 14 is swung forwardly at its lower end to the set position shown in Fig. 8.

For swinging the operating lever 14 to the set position, it has secured to it a screw 30, which extends outwardly through a slot 31 provided in the forward edge of the cover 7.

The releasing lever 9 is provided with a pawl 32 pivoted thereto and which is adapted to have its rear end engaged by the upper end of the operating lever 14, when the latter is swung from the set position by the spring 17.

The pawl 32 is normally forced into position for engagement with the lever 14 by a spring 33 which is secured to the lever 9. A stop pin 34 mounted in the lever 9 limits the upward swinging movement of the forward end of the pawl 32. A pin 35 secured to the plate 5 limits the downward swinging movement of the lower end of the releasing lever 9.

In operating the trigger mechanism, in ordinary service, the parts are disposed as shown in Fig. 7, that is, with the releasing lever 9 and the auxiliary trigger mechanism in the released position. After the hammer 1 has been cocked and engaged with the sear 2, as shown in Fig. 7, the main trigger 40 is pulled rearwardly at its lower end by pressing the finger against the concave portions 36 and 37 of the plate 5 and cover 7 respectively. The main trigger will thereby be swung upon the pin 6 against the abutment 13, thereby forcing the rear end of the sear 2 downwardly out of engagement with the hammer 1.

When it is desired to operate the auxiliary or hair trigger for accurate shooting, the screw 30 is forced forwardly in the slot 31, thereby swinging forwardly the lower end of the operating lever 14, thus placing a tension in the spring 17 by means of the link 21.

The arm 26 of the auxiliary trigger 25 will pass into engagement with the forward end of the abutment 27. The lever 14 will thus be held in the set position until the trigger 25 has been pulled rearwardly.

When the trigger 25 is in the set position, it will pass through the opening between the curved edges 36 and 37, so that the finger of the operator may force the trigger 25 rearwardly so as to release the arm 26 from the abutment 27. When this has been done,

the spring 17 will swing the lever 14 forwardly at its upper end, which upper end has passed to the rear of the pawl 32 when the screw 30 was forced forwardly to set the lever 14.

When the upper end of the lever 14 swings forwardly, it will engage the rear end of the pawl 32 which will swing the releasing lever 9 forwardly at its lower end, thereby depressing the pin 10, due to the fact that the roller 12 has a bearing against the fixed abutment 13, and causing the main trigger which carries the pin 10 to force downwardly out of engagement with the hammer 1 the sear 2, inasmuch as the main trigger is mounted on the pin 6 and has engagement at the right of said pin, as viewed in Fig. 8, with the lower side of the sear 2.

The operating lever 14 will swing the releasing lever 9 on the pin 10 until the lever 14 disengages with and passes forward of the rear end of the pawl 32. The parts will now be in the position shown in Fig. 7, excepting that the hammer will have been forced forwardly to the firing position.

The spring 17 is opposed to the spring 4, so that owing to its power being exerted through the levers 14 and 9, the auxiliary trigger mechanism will be easily operated and the auxiliary trigger 25 will be very sensitive and easily pulled. A very efficient and easily operated hair trigger mechanism is thus afforded.

I do not limit my invention to the structure shown and described, as modifications, within the scope of the appended claims, may be made without departing from the spirit of my invention.

What I claim is:

1. In a trigger mechanism, a main trigger, hammer engaging means releasable by said trigger, an operating member movable on said trigger, a spring, means for placing the spring under tension when the operating member is moved to a set position, an auxiliary trigger carried by the operating member for releasably holding the latter in the set position, a catch for releasably holding the auxiliary trigger in the set position, an abutment, and a releasing member movable against said abutment by said operating member, when the latter is operated by said spring, for releasing the hammer engaging means.

2. In a trigger mechanism, a main trigger, hammer engaging means releasable by said trigger, an operating member movable on said trigger, a spring, means for placing the spring under tension when the operating member is moved to a set position, an auxiliary trigger carried by the operating member for releasably holding the latter in the set position, a catch for releasably holding the auxiliary trigger in the set position, an

- abutment, and a releasing lever movable against said abutment by said operating member, when the latter is operated by said spring, for releasing the hammer engaging means. 5
3. In a trigger mechanism, a main trigger, hammer engaging means releasable by said trigger, an operating lever movable on said trigger, a spring, means for placing the 10 spring under tension when the operating lever is swung to a set position, an auxiliary trigger carried by said lever for releasably holding it in the set position, a catch for releasably holding the auxiliary 15 trigger in the set position, an abutment, and a releasing member movable against said abutment by said operating lever, when the latter is swung by said spring, for releasing the hammer engaging means. 20
4. In a trigger mechanism, a main trigger, hammer engaging means releasable by said trigger, an operating lever movable on said trigger, a spring, means for placing the 25 spring under tension when the operating lever is swung to a set position, an auxiliary trigger carried by the lever for releasably holding the lever in the set position, a catch for releasably holding the auxiliary trigger in the set position, an abutment, and 30 a releasing lever movable against said abutment, by said operating lever, when the latter is swung by said spring, for releasing the hammer engaging means. 35
5. In a trigger mechanism, a main trigger, an operating member movable thereon, spring actuated means for moving said member in one direction, an auxiliary trigger carried by the operating member for holding it in the set position, means for releasably holding the auxiliary trigger in the set 40 position, and a releasing member adapted to abut against a fixed part of a fire arm and movable by said operating member to the abutting position, when the operating member is moved from the set position by said spring actuated means. 45
6. In a trigger mechanism, a main trigger, an operating lever, spring actuated means for swinging the lever from a set position, 50 an auxiliary trigger carried by said lever for holding it in the set position, means for releasably holding the auxiliary trigger in the set position, and a releasing member adapted to abut against a fixed part of a 55 fire-arm and movable by said lever to the abutting position, when the lever is actuated by said spring actuated means. 60
7. In a trigger mechanism, a main trigger, a movable operating member, spring actuated means for moving said member from a set position, an auxiliary trigger carried by said member for holding it in the set position, means for releasably holding the auxiliary trigger in the set position, and a re- 65 leasing lever adapted to abut against a fixed part of a fire-arm and movable by said member to the abutting position when said member is moved by said spring actuated means. 70
8. In a trigger mechanism, a main trigger, an operating lever, spring actuated means for swinging the lever from a set position, an auxiliary trigger carried by said lever for holding it in the set position, means for releasably holding the auxiliary trigger in the set position, and a releasing lever 75 adapted to abut against a fixed part of a fire-arm and movable by the operating lever to the abutting position when the operating lever is swung by said spring actuated means. 80
9. In a trigger mechanism, a main trigger, a movable operating member carried by said main trigger, spring actuated means for moving said member from a set position, an auxiliary trigger pivoted to said member for holding it in the set position, means for releasably holding the auxiliary trigger in the set position, and a releasing lever adapted to abut against a fixed part of a fire-arm and pivoted to said main trigger and movable by 85 said member to the abutting position, when said member is operated by said spring actuated means. 90
10. In a trigger mechanism, a main trigger, an operating lever pivoted thereto, spring actuated means for swinging said lever from a set position, an auxiliary trigger pivoted to said lever for holding it in the set position, means for releasably holding the auxiliary trigger in the set position, and a releasing lever adapted to abut against a fixed part of a fire-arm and pivoted to said main trigger and movable by 95 said member to the abutting position, when the operating lever is swung by said spring actuated means. 100
11. In a trigger mechanism, a main trigger, a sear to which the trigger is pivoted, a releasing member adapted to bear against a fixed part of a fire arm, the trigger being also adapted to bear against said fixed part for moving the sear to the release position, spring actuated means for forcing the releasing member against the fixed part, an auxiliary trigger for releasably holding said 110 spring actuated means in the set position, and means for releasably holding the auxiliary trigger in the set position. 115
12. In a trigger mechanism, a main trigger, a sear to which the trigger is pivoted, a releasing lever adapted to bear against a fixed part of a fire arm, the trigger being also adapted to bear against said fixed part for moving the sear to the release position, spring actuated means for forcing the lever against said fixed part, an auxiliary trigger for releasably holding the spring actuated means in the set position, and means for re- 120 125

52 releasably holding the auxiliary trigger in the set position.

13. In a trigger mechanism, a sear, a main trigger pivoted to the sear and adapted to bear against a fixed part of a fire arm, a releasing member carried by the trigger and adapted to bear against said fixed part for swinging the sear, spring actuated means for forcing the releasing member against 10 said fixed part, an auxiliary trigger for releasably holding the spring actuated mechanism in the set position, and means for releasably holding the auxiliary trigger in the set position.

15. 14. In a trigger mechanism, a sear, a main trigger pivoted thereto and adapted to bear against a fixed part of a fire arm, a releasing member adapted to bear against said fixed part, spring actuated means including a lever for forcing said releasing member against said fixed part, an auxiliary trigger for holding said lever in the set position,

and means for releasably holding the auxiliary trigger in the set position.

15. In a trigger mechanism, a sear, a main trigger pivoted thereto and adapted to bear against a fixed part of a fire arm, a releasing lever adapted to bear against said fixed part, spring actuated means including a lever for forcing said releasing lever against 25 said fixed part, an auxiliary trigger for holding the second named lever in the set position, and means for releasably holding the auxiliary trigger in the set position.

16. In a trigger mechanism, a main trigger having a chamber provided with an opening, and an auxiliary trigger mounted in the chamber and in the set position extending through said opening, and in the released position being located wholly within 30 the chamber.

In testimony whereof I have signed my name to this specification.

ELZY R. WILLIAMS.
